IRONING MACHINE

John T. Hume, Chicago, Ill., assignor to Electric Household Utilities Corporation, Chicago, Ill., a corporation of Illinois

Application April 18, 1932, Serial No. 605,970

12 Claims. (Cl. 38—61)

This invention relates to improvements in ironing machines and its purpose is to provide a machine comprising relatively movable ironing elements which are actuated and controlled in an improved manner. The principal object of the invention is to provide an ironing machine comprising relatively movable ironing elements which are operated by mechanism controlled in a novel manner by the knee of the operator, thus leaving the hands of the operator free for manipulating the clothes being ironed. A further object of the invention is to provide an ironing machine comprising a rotatable roll and a relatively movable shoe in combination with driving mechanism and a controlling device located beneath the roll for controlling the rotation of the roll and the movement of the shoe. Still another object of the invention is to provide an ironing machine of the table type having a rotatable roll and an ironing shoe extending over the table with driving mechanism located at the ends thereof and means located beneath the table for controlling the rotation of the roll and the actuation of the shoe by the movement of the knee of the operator. A further object of the invention is to provide improved means for mounting an ironing shoe and an improved emergency release for effecting the movement of the shoe away from the roll when desired. Still another object of the invention is to provide an ironing machine comprising improved means for effecting the positive lubrication of the driving mechanism thereof. A further object is to provide an ironing machine having an extensible table for supporting the clothes being ironed. Other objects relate to various features of construction and arrangement which will appear more fully hereinafter.

The nature of the invention will be understood from the following specification taken with the accompanying drawings, in which one embodiment is illustrated.

In the drawings,

Fig. 1 shows a front elevation of the improved ironing machine of the present invention, with portions of the supporting legs broken away;

Fig. 2 is a detail sectional view taken on the line 2—2 of Fig. 1;

Fig. 3 shows a top plan view of the improved ironing machine illustrated in Fig. 1;

Fig. 4 shows a longitudinal section through the table on the line 4—4 of Fig. 3;

Fig. 5 shows an end elevation of the improved ironing machine, looking toward the left as viewed in Fig. 1;

Fig. 6 shows a transverse vertical section taken on the line 6—6 of Fig. 3;

Fig. 7 shows a vertical section on the line 7—7 of Fig. 1, thus illustrating in elevation certain parts of the driving mechanism contained within the housing with the cover of the housing removed;

Fig. 8 is a vertical section taken on the line 8—8 of Fig. 7, with the removable cover and associated parts in their normal positions;

Fig. 9 shows a transverse vertical section on the line 9—9 of Fig. 8;

Fig. 10 shows a longitudinal vertical section on the line 10—10 of Fig. 9;

Fig. 11 shows a horizontal section through the upper part of the housing on the line 11—11 of Fig. 8;

Fig. 12 is a horizontal section taken on the line 12—12 of Fig. 10;

Fig. 13 is a detail section of part of the mechanism for controlling the rotation of the roll;

Fig. 14 is a vertical section taken on the line 14—14 of Fig. 1;

Fig. 15 is a vertical section taken on the line 15—15 of Fig. 14;

Fig. 16 is a horizontal section taken on the line 16—16 of Fig. 14;

Fig. 17 is a vertical section similar to Fig. 14 but taken on the line 17—17 of Fig. 16; and

Fig. 18 is a vertical section similar to Fig. 17, showing the relative positions of the parts when the shoe has been released from engagement with the roll by the operation of the safety release device.

As illustrated in the drawings, the invention is embodied in an ironing machine comprising a table 20 having a flat table top 21 supported by four legs 22 which are also secured together by frame members 23 arranged in rectangular form. The table top 21 is provided adjacent one end 40 with a rectangular aperture 21^a, as shown in Fig. 7, in which is mounted an upwardly extending housing 24 having a removable cover 24^a and containing operating mechanism for actuating the rotatable ironing roll 25 and the relatively movable ironing shoe 26 which extend endwise therefrom above and parallel to the upper surface of the table top 21. The side frame members 23^a of the frame 23 are united by a horizontal plate 23^b which extends transversely beneath the table top and these members, as well as the end frame members 23^c, are preferably formed of sheet metal as one integral construction. The front and rear members 23^a, which form the side frame members, are connected by a pair of 55

transverse frame members 21 which serve to support parts of the controlling mechanism herein-after described. In order that the table top may be extended beyond the end of the ironing roll 25 for supporting articles of considerable size during the ironing operation, the table is provided with an extension 28 which slides above the plate 23^b of the frame with the reduced portion 28^a thereof engaged on opposite sides by the guide members 29 which are secured between the plate 23^b and the table top, as shown in Fig. 6. A pin 28^b projects from the part 28^a to engage one of the guide members 29 and thus limit the extent to which the table extension 28 may be withdrawn.

The ironing machine is driven by an electric motor 30 which is mounted on the table beneath the table top and within the rectangular frame 23, as shown in Fig. 1. The shaft 31 of this motor 20 extends horizontally, as shown in Figs. 3 and 5, through the end wall 23^c of the frame and has secured thereon a driving pulley 32 having an annular V-shaped groove engaged by a driving belt 33 which extends parallel to the end wall of the frame and passes around another similar pulley 34 secured upon a shaft 35. These parts are enclosed by a casing 36 which seats against the end of the table frame 23 and which has lugs 36^a secured to the under side of the table top by screws 37.

The shaft 35 is journaled in bearings 39 mounted in a hub 40 which is formed as an integral part of the removable cover 24^a of the housing which is secured in place by cap screws 41, with a gasket 42 interposed between the cover and the body of the housing, as shown in Fig. 8, so that an oil-tight enclosure is formed for the driving mechanism contained within the housing. This driving mechanism is in many respects 35 similar to that described and claimed in my prior Patent No. 1,712,958, dated May 14, 1929, but it embodies certain improved features herein-after pointed out. The hub 40 is provided with an oil hole 40^a leading to the space between the bearings 39 so that lubricating oil may flow to the shaft 35. The outer end of the hub 40 is provided with a recess in which is mounted a lubricating and oil retaining device 43 which is adapted to form a fluid-tight seal around the end of the shaft to prevent the escape of oil from the housing. At its inner end this shaft is journaled in a bearing 44 which is formed in a frame 45 by which many of the parts of the driving mechanism are carried. This frame 45 is provided with a plurality of bosses 46 which bear against other bosses 47 formed on the cover plate 24^a, as shown particularly in Figs. 9 and 10, and a series of studs 48 pass through the bosses 46 and threadedly engage the bosses 47 to secure the frame 45 to the cover plate 24^a so that when the cover plate is removed from the housing, the frame 45 and the parts of the driving mechanism carried thereby are removed with the cover plate as a unit.

The shaft 35 has secured thereon, between the 65 bearings 39 and the bearings 44, a driving pinion 50 which meshes with a gear 51 secured on a countershaft 52 which has one end journaled in a bushing 53 secured within a hub 54 formed on the cover plate 24^a, while the other end thereof 70 is journaled in a bushing 55 mounted in a hub 56 formed in the frame 45. The intermediate portion of this shaft 52 carries a relatively fixed pinion 57 which meshes with a driving gear 58 secured upon the hub of a pinion 59 which is rotatably mounted upon the enlarged portion 60.

of a driving shaft 60 which serves through one series of connections to rotate the ironing roll 25 and through another series of connections to effect relative movement of the ironing shoe 26 with respect to the ironing roll. The shaft 60 5 is journaled at one end in a bushing 61 carried by a hub 62 which is formed integrally with the outwardly projecting portion 24^b of the cover plate 24^a. The other end of this shaft 60 is journaled in a hub 62 formed as a part of the frame 10 45, as shown in Fig. 8. When the driving motor 30 is in operation, the gear 58 and the pinion 59 rotate continuously and mechanism is provided whereby these rotating members may be caused to rotate the roll or effect movement of the shoe 15 under the control of mechanism which is actuated by the knee of the operator beneath the table.

Proceeding first to describe the driving connections from the pinion 59 to the ironing roll 25, it will be seen that in Fig. 8 the pinion 59 is shown 20 as meshing with a gear 64 which is rotatably mounted on a shaft 65, the bushing 66 being interposed between the hub of the gear and the shaft. This shaft is slidably and longitudinally mounted in a bearing 67 which is formed in the 25 upper part of the frame 45 and it is provided at its inner end with a transverse slot 65^a engaged by the transverse flattened extremity 68^a of an aligning shaft 68 which is journaled in bushings 69 mounted in a tubular bore 70 formed in the 30 block 71 on the upper inner part of the housing 24. A collar 72 is secured on the shaft 68 to bear against the end of the block 71 and a tube 73 is secured to the hub 67 to extend around the collar 72 and embrace a circular boss formed on the 35 bearing block. The engagement of the flattened portion 68^a of the shaft 68 with the transverse slot 65^a of the shaft 65 permits relative endwise movement of the shaft 65 for the purpose of arresting the operation of the roll in the manner 40 herein-after described and also for the purpose of disengaging the driving connection when the cover plate 24 and frame 25 are removed from the housing.

The block 71 of the housing 24 is also provided 45 with a tubular bore 74 in which is secured a tubular axle 75, having the inner end thereof closed by a plug 76 to prevent the oil within the housing from escaping through the axle. The axle 75 projects longitudinally from the housing 50 24 parallel to the table top 21 at a point somewhat displaced rearwardly from the central longitudinal axis of the table top so that the operator sitting at the front of the table will have a 55 considerable space on the table in front of the roll which is mounted to revolve on this axle. The roll comprises a sheet metal cylinder 77 having wound thereon a number of layers of a fabric covering 79 adapted to contact directly with the 60 clothes being ironed. The sheet metal cylinder 77 has a metal disk 80 secured thereto adjacent each end thereof and these disks are secured by a ring 81 and studs 82 to annular bearing members 83 which revolve on bushings 84 secured on 65 the axle 75. At the inner end of the ironing roll 25, adjacent the housing 24, the bearing member 83 is provided with gear teeth 83^a which mesh with a driving pinion 85 secured on the shaft 68 so that when this shaft is rotated through the 70 connections herein-after described, the roll 25 is caused to revolve on the stationary axle 75.

The shaft 65 is provided within the hub 67 with a series of annular rack teeth 87 which mesh with a pinion 88 formed on a shaft 89 which is jour- 75

naled in the frame 45, as shown in Fig. 8. The teeth of the pinion 88 also mesh with the teeth of a rack bar 90 which is slidably mounted in a guide 91 carried by a frame 45, as shown in Fig. 13, and which is adapted to be reciprocated when certain mechanism is operated to remove the shoe 26 so that when the shoe is moved away from the roll, the rack bar 90 turns the shaft 89 to effect longitudinal movement of the shaft 65 and thereby arrest the rotation of the roll 25. The driving connection between the gear 64 and the shaft 65, which is thus broken by the longitudinal movement of the shaft 65, is established through a clutch member 94 which is splined upon the projecting extremity of the shaft 65, as shown in Fig. 8. This clutch member has an annular flange 94^a at its inner end provided with apertures 94^b which are engaged by clutch pins 95 projecting from the face of the gear 64. A disk 96 is secured on the end of the shaft 65 by a screw 97 and a coil spring 98 is mounted within a counterbored recess in the clutch member 94 to engage the edge of this disk and force the clutch member inwardly so that the apertures 94^b thereof are normally engaged by the clutch pins 95 to establish a driving connection between the gear and the shaft. When the shaft 65 is moved longitudinally, as above described, the bushing 66 thereon engages the end of the clutch member 94 and forces it longitudinally on the projecting end of the shaft 65 until the clutch pins 95 pass out of engagement with the apertures 94^b, thus permitting the gear 64 to continue its rotation without effecting the rotation of the ironing roll 25.

The movement of the ironing shoe 26 toward and from the ironing roll 25 is effected through the operation of an eccentric 100 which is secured on or formed as a part of the shaft 60 upon which the driving pinion 59 is journaled. This eccentric is journaled within a strap or hub 101 carried by one end of a connecting rod 102. This rod has a socket formed therein to receive a friction member 103 which is pressed by a spring 104 against the surface of the eccentric so that the accidental turning of the eccentric within its hub is prevented. The connecting rod 102 is pivotally connected at its lower end by a pin 105 with a crank arm 106 which is secured upon a rock shaft 107. As shown in Fig. 8, the crank arm 106 is mounted on the rock shaft 107 between the two hubs 108 which are carried by the cover plate 24^a and the frame 45, respectively. The shaft 107 is journaled in these hubs and extends therefrom through a stationary tube 110 which is secured within a hub 111 carried by the lower part of the housing 24. The shaft 107 is suitably journaled within this tube 110 which extends longitudinally beneath the table top 21 and the rock shaft is connected to the shoe in the manner hereinafter described so that when it is rocked in its bearings, it is adapted to effect movement of the shoe toward or from the roll upon the turning of the eccentric 100. The crank arm 106 has two angularly disposed parts 106^a and 106^b which are provided with a pin 112, shown in Figs. 8 and 9, arranged to engage an elongated slot 90^a formed in the lower end of the rack bar 90, previously described, and shown particularly in Figs. 9 and 13. When the eccentric 100 is operated to turn the rock shaft 107 and thereby move the shoe away from the roll, the pin 112 engages one end of the slot 90^a and thereby actuates the rack bar 90 to turn the shaft 89 and thereby shift the shaft longitudinally toward the right as viewed in Fig. 8, to disengage the clutch member 94 and there-

by arrest the rotation of the roll 25 simultaneously with the disengagement of the shoe 26. Upon movement of the eccentric 100 to rock the shaft 107 in the reverse direction and thereby restore the shoe 26 to ironing position with respect to the roll, the pin 112 on the crank arm 106 engages the other end of the slot 90^a to rotate the shaft 89 in the reverse direction and thus shift the shaft 65 toward the left, as viewed in Fig. 8, until it reaches its normal position, thereby allowing the clutch member 94 to move into engagement with the clutch pins 95 under the influence of the coil spring 98. The slot 90^a in the rack bar 90 is elongated because the angular movement of the crank arm 106 is greater than necessary to effect the required longitudinal movement of the shaft 65 and some lost motion is therefore permitted.

The driving connection between the shaft 60 and the pinion 59, which controls the rotation of the eccentric 100 for shifting the position of the shoe 26, is effected by a clutch member 115 formed on the face of the pinion 59 and a complementary clutch member 116 which is splined upon the shaft 60. The clutch member 115 is provided with recesses 115^a adapted to be engaged by clutch teeth 116^a formed on the face of the other clutch member. In addition to being splined on the shaft 60, the clutch member 116 has a tubular extension which is slidably mounted upon the hub 62 previously described and a coil spring 117 is mounted on this tubular extension between the cover plate 24^a and an annular shoulder 117^a formed on the clutch member so that the clutch member is normally forced by this spring toward a position wherein the clutch teeth 116^a engage the clutch recesses 115^a. The movement of the clutch member 116 away from the clutch member 115 is controlled by a shifter bar 118 which has a cylindrical end portion 118^a adapted to engage an annular groove 116^b in the clutch member and to coact with a cam surface 116^c which is formed around one side of this groove. The bottom of the groove is provided at two diametrically opposite points with recesses 116^d which are adapted to be engaged by the rounded extremity of the shifter bar 118 to hold the clutch member in either of two positions corresponding to successive rotations of the eccentric 100 through 180 degrees. When the shifter bar 118 engages either of these recesses, the eccentric 100 is held against rotation and at the same time the ironing shoe is held either in ironing position or in a position retracted from the shoe, depending upon which recess 116^d is engaged by the shifter bar. The engagement of the shifter bar with either recess 116^d is brought about simultaneously with the disengagement of the clutch members 115 and 116 by the coaction of the cylindrical portion 118^a of the shifter bar with the inclined cam surface 116^c on the clutch member. Assuming that the shifter bar is withdrawn from one recess, the clutch member 116 then engages the clutch member 115 and the shaft 60 is rotated by the pinion 59 while the eccentric 100 rotates through 180 degrees. As this occurs, the end of the shifter bar remains in engagement with the groove in the clutch member and coacts with the cam surface 116^c which is of such form that, at the end of 180 degrees of rotation of the shaft 60, the shifter bar forces the clutch member 116 toward the right, and disengages it from the clutch member 115, whereupon the end of the shifter bar is resiliently pressed into engagement with the other recess 116^d, thus holding the iron-

ing shoe in the position to which it has been moved.

The shifter bar 118 is pivotally connected at its upper end by a pin 119 to a crank arm 120 having an elongated hub 120^a which is journaled in a bearing 121 carried by the upper part of the frame 45, as shown particularly in Figs. 7 and 8. The lower portion of the shifter bar 118 is mounted to slide between a plate 122, which is secured to and spaced outwardly from the frame 45, and a guide plate 123 which is secured to the plate 122. A pin 124 projects outwardly from the shifter bar 118 to engage an elongated slot 123^a formed in the guide plate, thus limiting the longitudinal movement of the shifter bar. The shifter bar is normally forced downwardly into engagement with the groove of the clutch member 116 by means of a coil spring 125 which has its upper end attached to the pin 119 and its lower end connected to the plate 123. The shifter bar is moved out of engagement with the recess 116^a of the clutch member 116 by the turning of the crank arm 120 which is effected by another crank arm 126 secured by a set screw 127 on the opposite end of the elongated hub 120^a, as illustrated in Figs. 8 and 9. The outer end of the crank arm 126 is pivotally connected by a pin 128 to a connecting rod 129 which extends downwardly and is pivotally attached at its lower end by a pin 130 to a bell crank lever 131 having a hub journaled on a pin 132 projecting from the frame 45. This bell crank lever has a short arm 131^a extending downwardly in proximity to the upwardly extending arm or flange 133^a of a controlling member 133 which is secured upon the controlling shaft 135 which is capable of both a rotary movement and a longitudinal sliding movement, under the influence of the knee of the operator, as hereinafter described. When the shaft 135 and controlling member 133 are rotated in the direction indicated by the arrow 136, in Fig. 9, the arm or flange 133^a engages the short arm 131^a of the bell crank lever and rocks it about its pivot to effect an upward movement of the connecting rod 129. This turns the crank arms 120 and 126 in a direction to elevate the shifter bar 118 and thus release the clutch member 116 so that it is moved by the spring 117 into engagement with the other clutch member 115, rotating continuously with the driving pinion 59. The eccentric 100 is then actuated to turn the rock shaft 107 and thereby move the ironing shoe 26 toward or from the roll 25, depending upon the position it occupies at the commencement of the movement. A lug 133^b projects from the side of the controlling member 133 to engage the end of the arm 131^a of the bell crank lever and thus prevents the turning of the arm 133^a away from its operative position with respect to the bell crank lever under the weight of the knee-controlled devices hereinafter described.

In addition to performing the function of actuating the clutch member 116 to bring about the movement of the shoe 26 toward or from the ironing roll, the controlling member 133 also operates to actuate the clutch member 94 by which the rotation of the ironing roll is controlled. The latter function is brought about by the longitudinal shifting of the shaft 135 and this motion is transmitted to the control mechanism of the clutch 94 through a pair of flanges 133^c which are united with the flange or arm 133^a of the controlling member and extend therefrom transversely to the axis of the shaft 135. These flanges 133^c are arranged to receive between them the lower end of an upwardly extending lever 138 which is

pivoted at its upper end on a pin 139 carried by a bracket 140 secured to the top of the frame 45, as shown particularly in Figs. 7 and 9. The lever 138 is guided in its movement toward its lower end by a U-shaped bracket 141 which is secured to the frame 45 by screws 142. The lever 138 is pivotally engaged some distance below its upper end by a pin 143^a secured upon an arm 143 which is fixed in the slot of a head 144^a formed on the end of a rod 144 having a sliding engagement with the hollow hub 120^a of the crank arm 120 previously described. This rod 144 extends completely through the hub 120^a as shown in Fig. 8, and has secured to the forward end thereof a depending plate 145 provided at its lower end with a slot 145^a to receive the intermediate portion of the clutch member 94. When the member 145 is shifted toward the right, as shown in Fig. 8, this plate 145 engages the annular flange 94^c of the clutch member and thus disengages it from the pin 95 so that the gear 64 is then free to rotate without effecting the rotation of the roll 25. When the pressure on the member 145 is released by removing the knee pressure which has shifted the shaft 135 longitudinally, the clutch member 94 is automatically returned by the spring 98 into engagement with the clutch pins 95 of the gear 64.

The controlling shaft 135 is journaled in a bearing 146 mounted in the wall of the casing 24, as shown in Fig. 10, and is surrounded by an oil retaining device 147 set in a recess in the wall of the casing to prevent the escape of oil around the shaft. From the bearings 146, the shaft 135 extends horizontally beneath the table top 21 and is journaled in bearings carried by the transverse frame members 27 and by a bracket 148 secured to the under side of the table top, as shown in Fig. 3. It is normally returned to its normal position by longitudinal movement away from the casing 24 through the action of a coil spring 150 which is mounted thereon with one end abutting against one of the frame members 27 and the other end engaging a collar 151 secured thereon, as shown particularly in Figs. 3 and 16. At a point between the casing 24 and the transverse frame members 27, the shaft 135 has secured thereon an arm 152 carrying at its end a roller 153 which bears upon the tube 110, enclosing the rock shaft 107, as shown in Fig. 2, for the purpose of holding the shaft 135 in its normal angular position after being released by the knee of the operator. The angular movement of this shaft 135 is effected by crank arms 154 secured thereon adjacent its ends and having their outer ends connected to the horizontal rod 155 adapted to be engaged by the knee of the operator with an upward movement for rocking the shaft 135 in its bearings and thereby turning the controlling member 133 in the direction of the arrow 136, shown in Fig. 9. The rod 155 has a pair of spaced arms 156 secured thereon and adapted to extend on opposite sides of the knee of the operator so that the rod 155 and the shaft 135 may be moved longitudinally, toward the right as shown in Fig. 1, against the compression of the spring 150, for the purpose of actuating the lever 138 and thereby disconnecting the clutch 94 which controls the rotation of the ironing roll 25. These knee-engaging arms 156 have split hubs 156^a which are clamped on the rod 155 by thumb screws 157 so that their spaced relation and position on the rod 155 may be varied to suit the convenience of the operator.

The tube 110 which houses the rock shaft 107 is secured at one end in the hub 111 carried by the housing 24, as previously described, and it

extends horizontally therefrom beneath the table top 21 with the other end thereof engaging a bearing block 160 carried by one of the frame members 27 and having the end portion of the rock shaft journaled therein, as shown in Figs. 3 and 16. The extremity of the rock shaft 107 is reduced in diameter as shown at 107^a in Fig. 16 and is journaled in a bearing 161 carried by the other transverse frame member 27. Between these frame members 27, the rock shaft 107 has secured thereon an upwardly extending crank arm 162, the upper end of which is split to provide a pair of ears 162^a adapted to receive between them a connecting rod 163 which is pivotally connected thereto by a pin 164. A looped wire spring 165 straddles the link 163 with the loop thereof bearing against a shoulder 165^a on its under side. The arms of the spring then extend upwardly over the ears 162^a of the crank arm 162 and are then reversely bent to pass through the slot between the ears on the under side of the connecting rod 165, as shown particularly in Figs. 14, 16, 17 and 18. This spring tends to elevate the connecting rod 163 about the pivot pin 164 for a purpose hereinafter described. The connecting rod 163, which is adapted to effect the movement of the ironing shoe 26, upon angular movement of the rock shaft 107, extends rearwardly from the crank arm 162 and has its rear end pivotally connected by a pin 166 with a pair of links 167 which are located on opposite sides thereof and which are in turn embraced by the side plates 168^a of a yoke 168, pivotally connected with the links 167 by a pin 169. This pin 169 is clamped to the supporting arm 170 of the ironing shoe 26 and it is adapted to engage a slot 165^b formed in the upper side of the connecting rod 165 so that when the parts are in their normal positions, the pin 169 is seated within this slot and the parts have the relative arrangement shown in Fig. 14. The pin 169 is clamped to the supporting arm 170 of the ironing shoe by means of a strap 172 which has arms located on opposite sides of a slot 170^a formed in the lower end of the arm 170 to receive the members 165, 167 and 168. The straps 172 are secured to the lower end of the supporting arm 170 by bolts 173 and they extend around an eccentric sleeve 174 which is journaled on a bolt 175 engaging bosses 176 formed on the frame members 27 and clamped in position therein by bolts 177. This eccentric sleeve 174 is provided with transverse holes 174^a into which a tool may be inserted through the radial slot 173^a formed in the cylindrical portion of the strap, thus permitting it to be turned in order to change the position of the shoe supporting member 170 about the rod 169 which bears against the rear side thereof, thus regulating the pressure with which the shoe bears against the clothes on the ironing roll. The yoke 168 has a forwardly extending arm 168^b which has its forward end turned laterally, as shown at 168^c in Fig. 16, and provided with a notch 168^d on its upper side to receive a wire hook 177 carried by the rear end of an operating handle 178 which extends forwardly and rests upon the shaft 135 with the forward end thereof curved to form a handle 177^a, as shown in Fig. 6, which may be engaged by the hand of the operator to effect the release of the shoe 26 from engagement with the roll in case of emergency.

The shoe supporting arm 170 is in the form of a flat leaf spring having considerable width and it extends upwardly from the actuating mechanism just described through an opening 21^c in the table top, as illustrated in Fig. 14. A metal plate 180 is

provided with a slot to fit the arm 170 and rests upon the table top to close the aperture 21^c. A guard plate 181 is mounted over the plate 180 and secured to the table top with an elongated slot 181^a therein to permit angular movement of the arm 170 during the movement of the shoe toward and from the roll. The moving parts are thus protected from entanglement with the clothes being ironed. The upper end of the arm 170 is curved inwardly toward the ironing roll and provided with a cylindrical sleeve or hub 170^b which extends between the two flanges 182^a of a bracket 182 secured to the rear side of the ironing shoe 26. The hub or sleeve 170^b of the supporting arms is pivotally connected to these flanges 182^a by a bolt 183. A spring 184 is mounted on the bolt 183 with the ends thereof engaging the supporting arm 170 and the lower edge of the shoe to cause this lower edge to engage the clothes on the roll 25 in advance of the engagement therewith of other parts of the shoe when the shoe is moved toward the roll. The shoe 26 comprises a curved plate 185 having an ironing surface which is concentric with the axis of the roll when the shoe is in its ironing position. This plate has its upper edge 25 deflected upwardly as shown at 185^a to facilitate the passage of the clothes beneath the shoe as the roll rotates in the direction indicated by the arrow 186 in Fig. 7. The plate 185 is further provided with flanges 185^b along its upper and lower edges which hook over the relatively fixed back plate 187 having a recess therein which is occupied by the usual electrical heating element having a connection with a source of current supply so that the shoe is heated electrically during the process of ironing. The shoe 26 is preferably provided adjacent one end thereof with a projecting horn 188 which is occupied by an electric heating element connected with the circuit of the main heating element of the shoe so that this horn 40 may be heated and may be employed to smooth, by rubbing over its rounded surface, those small portions of garments being ironed which are not readily ironed by passing between the roll 25 and the shoe 26.

The supporting arm 170, being located midway between the ends of the shoe 26, supports the shoe in balanced position and, because of its resilience, maintains a resilient pressure of the shoe against the roll or the clothes passing around the roll. In ordinary operation, the shoe 26 is merely moved toward and from the roll by the rocking of the arm 170 about the eccentric sleeves 174 under the influence of power transmitted thereto through the connecting rod 163 and associated parts from the rock shaft 107 which is actuated by the eccentric 100, as previously described. The connecting rod 163 normally occupies the position shown in Fig. 14, wherein the pivot pin 166 is swung upwardly so that a straight line connecting the axis of the pin 166 and the axis of the pin 164 lies above the axis of the pin 169. The toggle connection which is thus formed between the connecting rod 163 and the supporting arm 170 through the links 167 and the yoke 168 is such as to maintain the connecting rod 163 in the position shown in Fig. 14 so that the motion of the crank arm 162 is transmitted to the shoe supporting arm 170. However, in case of emergency, as when the fingers of the operator are drawn between the shoe 26 and the roll 25, the operator may use the other hand to seize the handle 178 and press downwardly on the forward end thereof with the result that the rear end is elevated about the shaft 135 as a fulcrum. This raises the arm 168^b of the yoke and depresses 75

the rear end of the connecting rod 163 by the engagement therewith of the top wall 168^c of the yoke until a line connecting the axes of the pins 164 and 166 lies slightly below the axis of the pin 169, as shown in Fig. 17. The resilient pressure of the supporting arm 170, which is then in engagement with the clothes on the roll, causes the links 167 to swing downwardly about the pin 169, to break the toggle connection, as shown in Fig. 18, and permit the arm 170 to swing rearwardly away from the roll. In order to restore the parts to the relationship shown in Fig. 14, the ironing mechanism may be operated by shifting the controlling shaft 135 with the knee of the operator to engage the clutch 116 and cause the eccentric 100 to swing the crank arm 162 toward the rear, as shown in Fig. 18, whereupon the connecting rod 163 is pushed rearwardly and rocks the links 167 upwardly about the pivot pin 169. This motion, which is assisted by the coil spring 165 engaging the connecting rod 163, will cause the rod 163 to snap back to the normal position shown in Fig. 14.

From the foregoing description it will be seen that when the knee of the operator is moved upwardly, the upward motion of the rod 155, shown in Figs. 1 and 6, causes a rotation of the controlling shaft 135 in the direction indicated by the arrow 136 in Fig. 9. This causes the controlling member 133 to rock the bell crank lever 131, thereby turning the cranks 126 and 120 and elevating the shifter bar 118 out of engagement with the recess 116^d of the clutch member 116 which has previously been engaged thereby. Assuming that the shoe has previously been in ironing position with respect to the roll 25, the result of thus elevating the shifter bar 118 is to permit the clutch member 116 to be moved into driving engagement with the rotating clutch member 115 by the coil spring 117. The shaft 60 is then rotated with a corresponding rotation of the eccentric 100 which transmits its motion through the connecting rod 102 and crank arm 106 to the rock shaft 107. This rock shaft is then turned in its bearings in a direction adapted to move the crank arm 162 toward the right, as shown in Fig. 14, and thereby move the shoe 26 away from the roll 25. Simultaneously with this movement of the shoe, the crank arm 106 on the rock shaft 107 actuates the rack bar 90 through the pin 112 and thus turns the shaft 89, shown in Figs. 8 and 13, to cause the shifting of the shaft 65 toward the right as viewed in Fig. 8. The bushing 66 on this shaft then engages the clutch member 94 and forces it against the spring 98 out of engagement with the clutch pins 95, thus permitting the gear 64 to rotate without rotating the ironing roll 25. In this way, the driving connection to the roll 25 is automatically broken each time that the controlling mechanism is operated to move the shoe 26 away from the ironing roll.

It will be apparent that the movement of the shoe away from the roll which has just been described is effected by a half revolution of the eccentric 100 and that, at the end of this half revolution, the shifter bar 118 operates by coaction with the cam surface 116^c on the clutch member 116 to disengage this clutch member and stop the rotation of the eccentric. At the same time, the shifter bar 118 is pressed by the spring 125 into engagement with one of the recesses 116^d of the clutch member so that this clutch member and the shaft 60 are then held against rotation and the shoe 26 is held in its retracted position. When the operator wishes to move the shoe toward the roll, in readiness for ironing, the rod 155 is again

elevated by the knee of the operator to turn the controlling shaft 135 and thereby again effect the operation of the bell crank lever 131 and rod 129 to rotate the crank arms 126 and 120 and withdraw the shifter bar 118 from the recess 116^d last engaged thereby. This permits the clutch member 116 to engage the clutch member 115 under the influence of the spring 117 so that the eccentric 100 completes another half revolution, at the end of which the clutch member 116 is again disengaged automatically by the shifter bar 118 and is held against rotation by the engagement of that shifter bar with a recess 116^d so that the shoe 26 is then held in ironing position. At the same time that the shoe 26 is thus restored to its ironing position, the rack bar 90 is again actuated by the engagement of the pin 112 with the other end of the slot 90^c so that the shaft 89 is turned in a direction to move the shaft 65 toward the left, as viewed in Fig. 8, and thereby permit the clutch member 94 to reestablish a driving connection between the gear 64 and the shaft 65.

In addition to this automatic disengagement of the driving connection to the ironing roll, simultaneously with the movement of the shoe away from the roll, the rotation of the roll may be arrested, with the shoe 26 in ironing position, by causing an endwise motion of the controlling shaft 135 through a lateral shifting of the knee 30 of the operator located between the arms 156 on the rod 155. When that endwise movement of the shaft 135 takes place, toward the right as viewed in Fig. 10, the lever 138 is actuated to shift the rod 144 toward the right, as viewed in Fig. 8, thereby causing the plate 145 to move the clutch member 94 out of engagement with the clutch pins 95 and permit the gear 64 to rotate without rotating the roll. The clutch 94 remains disengaged as long as the knee of the operator is pressed against one of the arms 156 to maintain the controlling shaft 135 in its shifted position. This may be desirable when the operator wishes to arrest the rotation of the roll 25 momentarily when there is passing between the roll 25 and the shoe a portion of the garment which could not be sufficiently ironed by one continuous passage over the surface of the shoe. As soon as the pressure of the knee of the operator is released, the spring 150, shown in Figs. 3 and 16, restores the operating shaft 135 to its normal position and thus permits the clutch member 94 to be moved again into engagement with the clutch pins 95 under the influence of the coil spring 98.

The mechanism which drives the roll and effects relative movement of the shoe with respect to the roll is also employed for bringing about a positive lubrication of all parts of the driving mechanism contained within the housing 24. This housing is adapted to be partially filled with lubricating oil which may be inserted through an aperture in the upper part of the cover 24^a which is normally closed by a threaded plug 190, shown in Fig. 8. When it is desired to replace this oil, it may be drained out through an aperture in the lower part of the housing which is normally closed by another plug 191, shown in Fig. 10. The lower part of the housing is thus always occupied by a considerable quantity of lubricant and, for the purpose of elevating this lubricating material and positively feeding it to different parts of the driving mechanism, a pump 193 is positioned in the 75

lower part of the housing and arranged to be actuated by the driving mechanism. This pump comprises a cylinder 194 having a lug 194^a resting on the bottom of the housing, as shown in Figs. 7 and 9, and having an upwardly extending flange 194^b which is secured to a boss on the housing 24 by a stud 195, as shown in Figs. 7, 8 and 9. The end of the pump casing, opposite the flange 194^b, engages a groove 196^a formed in a boss 196 on the housing so that the pump cylinder 194 is slidably engaged by a piston or plunger 197 which projects therefrom and carries a laterally extending pin 198 arranged to engage a slot 199 formed in the end of a crankarm 199 fixed on the rock shaft 107. The pump casing is provided on its under side with an inlet port 200 which is normally closed by a ball valve 201 seated by gravity. When the rock shaft 107 is turned to move the plunger 197 toward the right, as viewed in Fig. 7, the suction created thereby elevates the ball valve 196 and draws lubricating oil into the cylinder of the pump. Upon the reverse movement of the plunger 197, due to the opposite motion of the rock shaft 107, the pressure of the oil in the pump cylinder seats the ball valve 201 and forces upwardly another ball valve 202 which normally closes an outlet port 203 located in a valve member 204 mounted in the upper end portion of the pump casing. When the ball valve 202 is moved upwardly to open the outlet port, the oil from the pump cylinder 194 is discharged upwardly through a pipe 205. This pipe extends vertically within the casing 24 and is provided at its upper end with a curved extremity 205^a which is adapted to discharge the oil into a pan or tray 206, shown in Fig. 11, which is formed as an integral part of the upper portion of the frame 45.

The pan 206 forms an oil reservoir from which the oil flows downwardly through a passage 207 to the bearing of the shaft 65, as shown in Fig. 8. The oil then finds its way through the hub 61 to the bearings of the shaft 65 and gear 64 and also to the bearing of the shaft 89, from which point the oil flows downwardly through another passage 208 to the bearing 62 of the shaft 60. From this bearing hub, another oil passage 209 conveys the oil downwardly to the bushing 55 in which one end of the shaft 52 is journaled. The bushing 53 and hub 54 in which the other end of this shaft is journaled have an oil hole 210 through which oil, dripping from the parts above, finds its way to this end of the shaft. From the hub 56, the oil flows downwardly by gravity through another oil passage 211 to the hub 44 in which one end of the shaft 35 is journaled. The other end of this shaft is lubricated by oil dripping downwardly from above and finding its way through the oil hole 40^a previously described. In this way there is a positive supply of oil to the upper part of the frame 45 upon each complete actuation of the rock shaft 107 for moving the ironing shoe 26 toward and from the roll 25. The principal bearings of the driving mechanism are lubricated directly by oil flowing from the pan 206 through the oil passages just referred to and the other parts of the mechanism are lubricated by oil dripping from the ends of these bearings and by possible overflow from the pan 206. The 75 bearings of the rock shaft 107 are lubricated

by the body of oil which collects in the bottom of the casing 24 and any excess of lubrication supplied to the oil passages from the pan 206, either flows out at the ends of the various bearings or is returned to the bottom of the casing 212 leading downwardly from the bearing 44.

Although one form of the invention has been shown and described by way of illustration, it will be understood that it may be constructed in various other embodiments coming within the scope of the appended claims.

I claim:

1. The combination in an ironing machine, of a table, a housing carried by said table, ironing elements carried by said housing and extending over said table, driving mechanism located in said housing for actuating said ironing elements, a rotatable and axially movable shaft extending from said housing beneath said table, means adapted to be engaged by a knee of the operator for effecting the movements of said shaft, and connections from said shaft to said driving mechanism for causing the rotatable movement of said shaft to control one operation of said mechanism and for causing the axial movement of said shaft to control another operation of said mechanism.

2. The combination in an ironing machine, of a rotatable roll, a relatively movable shoe, driving mechanism, means for connecting said driving mechanism to rotate said roll, means for connecting said driving mechanism to move said shoe toward and from said roll, a controlling member located beneath said roll and having rotatable and longitudinal movements adapted to be effected by the knee of the operator, and connections from said controlling member to said driving mechanism for causing the rotatable movement of said controlling member to control the rotation of said roll by said driving mechanism and for causing the longitudinal movement of said controlling member to control the movement of said shoe toward and from said roll.

3. The combination in an ironing machine, of a table, a rotatable roll and a relatively movable shoe mounted over said table, driving mechanism, means including a controlling member having reciprocatory and rotary movements for controlling the operation of said driving mechanism in rotating said roll and effecting said movement of said shoe respectively, and a member extending beneath said table and actuated by the operator for actuating said controlling member.

4. The combination in an ironing machine, of a table, a housing carried by said table, an ironing roll and a shoe extending longitudinally from said housing over said table, driving mechanism in said housing, a shaft having a sliding and rotatable engagement with the wall of said housing and extending beneath said table, a controlling member mounted on said shaft within said housing, means actuated by the angular movement of said controlling member for causing movement of said shoe with respect to said roll, and means actuated by linear movement of said controlling member to control the rotation of said roll by said driving mechanism.

5. The combination in an ironing machine, of a rotatable roll, a relatively movable shoe, driving mechanism, means including a clutch to connect said driving mechanism to rotate said roll, means including a second clutch to connect said driving mechanism to move said shoe with respect to said roll, and a controlling member having movement in one direction to operate one

of said clutches and movement in another direction to operate the other of said clutches.

6. The combination in an ironing machine, of a rotatable roll, a relatively movable shoe, driving mechanism, means including a clutch to connect said driving mechanism to rotate said roll, means including a second clutch to connect said driving mechanism to move said shoe with respect to said roll, a controlling member having movement in one direction to operate one of said clutches and movement in another direction to operate the other of said clutches, and means adapted to be actuated by the knee of the operator for imparting said movements to said controlling member.

7. The combination in an ironing machine, of a rotatable roll, a relatively movable shoe, driving mechanism, means including a clutch to connect said driving mechanism to rotate said roll, means including a second clutch to connect said driving mechanism to move said shoe with respect to said roll, and means including a controlling member having movement in one direction for engaging one of said clutches and disengaging the other of said clutches and having movement in another direction for independently disengaging said first named clutch.

8. The combination in an ironing machine, of a rotatable roll, a relatively movable shoe, driving mechanism, means including a clutch to connect said driving mechanism to rotate said roll, means including a second clutch to connect said driving mechanism to move said shoe with respect to said roll, a controlling member having movement in different directions, means actuated by the movement of said controlling member in one direction for effecting operation of said second named clutch, means operated by the actuation of said second named clutch to effect the disengagement of said first named clutch, and means actuated by the movement of said controlling member in another direction for independently effecting the disengagement of said first named clutch.

45 9. The combination in an ironing machine, of a rotatable roll, a relatively movable shoe, driving mechanism, means including a clutch to connect said driving mechanism to rotate said roll, means including a second clutch to connect said

driving mechanism to move said shoe with respect to said roll, a controlling member having movement in different directions, means actuated by the movement of said controlling member in one direction for effecting operation of said second named clutch, means operated by the actuation of said second named clutch to effect the disengagement of said first named clutch, means actuated by the movement of said controlling member in another direction for independently effecting the disengagement of said first named clutch, and means adapted to be actuated by a knee of the operator for imparting said movements to said controlling member.

10. The combination in an ironing machine, of a rotatable roll, a relatively movable shoe, driving mechanism, means operated by said driving mechanism for moving said shoe toward and from ironing position with respect to said roll, means for starting the rotation of said roll by said driving mechanism when said shoe is moved to ironing position and for stopping the rotation of said roll when said shoe is moved away from ironing position, and means located beneath said roll in a position to be actuated by the knee of the operator and having connections with said driving mechanism for independently stopping the rotation of said roll when said shoe is in ironing position.

11. The combination in an ironing machine, of a rotatable roll, a relatively movable shoe, a controlling member having rotary and axial movements, means controlled by one of said movements of said member for effecting the rotation of said roll, and means controlled by the other of said movements of said member for effecting movement of said shoe toward and from said roll.

12. The combination in an ironing machine, of a rotatable roll, a relatively movable shoe, driving mechanism for rotating said roll and moving said shoe, controlling means including a rotatable and axially movable shaft, means actuated by the axial movement of said shaft for controlling the rotation of said roll by said driving mechanism, and means actuated by the rotary movement of said shaft for controlling the relative movement of said shoe by said driving mechanism.

JOHN T. HUME.
